CLAIM

The ornamental design for a combined bed and tables therefor, as shown and described.

DESCRIPTION

FIG. 1 is a top front and right side perspective view of a combined bed and tables therefor, embodying my new design;

FIG. 2 is a top plan view thereof;

FIG. 3 is a right side elevational view thereof, the left side view being a mirror image thereof;

FIG. 4 is a front elevational view thereof; and

FIG. 5 is a rear elevational view thereof.

FIG. 1

FIG. 2

FIG. 3

FIG. 4

FIG. 5
